[57] **CLAIM**

The ornamental design for a stone guard for an automobile fender, substantially as shown and described.

DESCRIPTION

FIG. 1 is a front elevational view of a stone guard showing my new design as associated with the rear fender of an automobile with the automobile shown in broken lines for illustrative purposes only;

FIG. 2 is an enlarged right side elevational view thereof;

FIG. 3 is an enlarged rear elevational view thereof;

FIG. 4 is an enlarged left side elevational view thereof;

FIG. 5 is an enlarged top plan view thereof;

FIG. 6 is an enlarged bottom plan view thereof; and

FIG. 7 is a sectional view thereof taken along line 7—7 in FIG. 3.
